UNITED STATES PATENT OFFICE.

LEWIS MILLER, OF PHILADELPHIA, PENNSYLVANIA.

HYDRAULIC PRESS.

SPECIFICATION forming part of Letters Patent No. 394,383, dated December 11, 1888.

Application filed August 9, 1888. Serial No. 282,317. (No model.)

To all whom it may concern:

Be it known that I, LEWIS MILLER, a citizen of the United States, residing at Philadelphia, in the county of Philadelphia and State of Pennsylvania, have invented certain new and useful Improvements in Hydraulic Presses, of which the following is a specification, reference being had therein to the accompanying drawings, in which—

10 Figure 1 represents a side elevation of my improved apparatus complete and connected to a hydraulic cotton-press; Fig. 2, a plan view of the same, partly in section, the press and the engines not being shown; Fig. 3, a transverse 15 sectional view on the line *c d* of Fig. 2; Fig. 4, a section on the line *a b* of Fig. 2; Fig. 5, a sectional view of one of the automatic pressure-controllers adapted to disengage the sliding 20 clutches from the stationary clutch-wheels when the required pressure is attained in the rams, also showing one of the automatically-closing check-valves located in the conduits between the rams and the press; Fig. 6, a section 25 on line *x x* of Fig. 2; Fig. 7, a detail view of the spring-catch secured to the automatic drop-valves. Fig. 8 is a detail view of a slight modification, hereinafter fully described.

This invention has relation to that class of hydraulic presses wherein two rams are employed to force the pressing-liquid into the cylinders of the press, the two rams being adapted to operate successively, one (the primary or low-pressure ram) imparting the light initial pressure to the bale and the other (the secondary or high-pressure ram) imparting the final heavy pressure, as will be fully hereinafter set forth.

The special object of this invention is to provide an improved system or apparatus for successively operating these hydraulic rams which will be comparatively economical in the consumption of fuel, efficient and very rapid in operation, and which will be capable of exerting a very great pressure, as will be more fully hereinafter stated.

In the accompanying drawings, the letter A, Fig. 1, designates a hydraulic press of that character shown in my Letters Patent numbered 367,220, and granted on the 26th day of July, 1887. Connected to the leader-pipes B of this press by means of conduits C C' are the two hydraulic cylinders D D', these being

supported upon and bolted to suitable bed-plates and foundations and provided with lateral perforated arms or ears E. Working in the ram-cylinders are the hollow reciprocating rams or plungers F F', the former being the primary or low-pressure ram and the latter the secondary or high-pressure ram. Bolted or otherwise attached to the rear ends of these rams are the rack-bars G G', provided with teeth on their upper faces and forwardly-inclined or beveled projections H H' upon their rear ends, as shown in Fig. 2.

Mounted in standards or bearings I I and I' I', bolted to suitable bed-plates, J, and foundations J' in the rear of the rams, is a strong transverse shaft, K. The standards I I' are each connected to the lateral perforated ears E, formed on the ram-cylinders, by means of a very strong connecting-rod, L, these rods passing through horizontal apertures in the ears and standards and securely held in place by the gibs or wedges a, passing vertically through the rods and ears E, and the tightening nuts a', tapped on the rear ends of the rods and adapted to clamp the standards.

The rack-bars G G' pass under the shaft K and rest upon anti-friction rollers b, journaled in suitable ears upon the bed-plates J. Engaging with the rack-bars and journaled loosely upon the shaft K are the pinions M M', provided with clutch-teeth upon their inner faces, these clutch-teeth being adapted to engage at proper intervals with similar teeth 85 upon sliding clutch-wheels N N' upon the shaft. These latter clutch-wheels N N' have a limited reciprocating movement upon the shaft K between the inner bearings or standards, I I', and the pinions M M', and are caused 90 to rotate with the shaft by means of feathers b', embedded in the shaft, as clearly shown in Fig. 3. Inserted in annular grooves in the sliding clutches N N' are divided collars O O', and pivotally connected to these collars are the 95 bifurcated ends of angle-levers P P', pivoted upon suitable supports, c. The collars O O' are clamped loosely in the grooves in the sliding clutches, so as to permit the latter to rotate freely without rotating the collars. The 100 sliding clutches are also provided with peripheral flanges or projections d, for a purpose hereinafter stated.

Bolted or otherwise secured to and commu-

nicipating with the interior of the conduits C C' are the short vertical cylinders Q Q' of the pressure-controllers, these cylinders being provided with vertically-working plungers or 5 pistons R R', which normally rest at the bottom of the said cylinders. The rods of these plungers are pivotally connected to the weighted angle-levers S S', pivotally supported upon standards e upon the caps of the vertical cylinders Q Q'. The shorter arms of the levers S S' are connected, respectively, to the shorter arms of the angle-levers P P' by connecting-rods T T' or other suitable means.

The letters U U' designate spring-catches 15 provided with notches at their upper ends to automatically receive and retain the longer arms of the angle-levers S S' when they are elevated by the upward movement of the plungers R. When it is desired to disengage 20 these catches from the levers in order to permit the plungers R to fall, the operator may do this by hand directly, or by means of suitable levers and connecting-rods attached to the spring-catches, as shown by dotted lines 25 in Fig. 7.

Journaled in suitable standards, W, located to the rear of the shaft K, is the main driving-shaft X, provided midway its length with a pinion, Y, which engages with a large spur- 30 wheel, Z, rigidly secured on the center of the said shaft K, and upon its ends with large spur-wheels A'. Journaled in suitable standards or bearings located to the rear of the main shaft X are the two independent driving-shafts, B', each of which is provided with a pinion, B'', adapted to intermesh with the spur-wheels A' on the main shaft. Attached to and adapted to rotate these driving-shafts are two independent high-speed steam-engines, C'', one of which is shown in Fig. 1. In this figure I have shown an ordinary vertical reciprocating steam-engine; but it is evident that I may use a rotary engine or any other pattern in lieu thereof.

45 In Fig. 5 one of the vertically-working check-valves, D'', is shown, these valves being placed in the conduits C C' to automatically close when the rams attain their maximum pressure. The lower stems of these valves extend through suitable stuffing-boxes in the bottom of the conduits C C'. By means of these projecting stems the operator may raise the valves to permit the pressing-liquid to run back into the ram-cylinders D D' after each 55 pressing operation.

A suitable amount of pressing-liquid having been introduced into the rams and conduits and the engines having been started, the operation of the apparatus is as follows: 60 The motion of the drive-shafts of the engine will be communicated to the shaft K through the medium of the pinions and spur-wheels, and this shaft will be kept continuously revolving whether the rams be in operation or 65 not, carrying with it the sliding clutch-wheels N N'. After the bale is in place in the press and it is desired to operate the low-pressure

ram D, the operator disengages the spring-catch U from the angle-lever S. When thus released, the longer arm of the angle-lever and 70 the plunger R are carried down by means of the weight on the lever, and this movement of the lever serves, through the medium of the connecting-rod, bifurcated lever P, and collar O, to throw the rotating clutch-wheel 75 N into engagement with the loose pinion M on the shaft K. As the shaft K revolves, it now carries with it the loose pinion M, and this pinion serves to advance the rack-bar G and ram F. As the ram F advances, the fluid 80 in the cylinder D is forced out through the conduits, past the check-valve, and into the cylinders of the press. As soon as the maximum pressure of this ram is attained (this maximum pressure being regulated by means 85 of the adjustable weights on the angle-lever S) the piston R will be elevated by the fluid, and, through the medium of the connecting rods and levers, disengage the sliding clutch-wheel N, and thus stop the movement of the 90 ram. The instant the forward movement of the ram is arrested, the check-valve D'' in the conduit C will automatically close upon its seat and cut the ram off from communication with the conduits leading to the press. 95 When the longer arm of the weighted angle-lever S is elevated by the piston R, it automatically engages the notch in the spring-catch, and is thereby held in an elevated position, holding the clutch N out of engagement. By disengaging the weighted lever S' from its catch the rotating pinion N' will be thrown into engagement with the pinion M' and the secondary or high-pressure ram F' operated to impart the final pressure to the 100 bail. When the maximum pressure of this ram is attained, the forward movement of the plunger is arrested in the same manner as the low-pressure ram, and the instant the plunger stops, the check-valve D'' in the conduit C' 105 will automatically close and prevent the backward flow of the liquid into the ram-cylinder. When the bale has been properly tied and bound, the operator will open the check-valves 110 D'' and permit the pressing-liquid to run back into the ram-cylinders and force the plungers or rams back to their original position.

In case the pressure-controller or shifting-levers should become disarranged and fail to 115 operate, to prevent injury to the apparatus I provide means for positively disengaging the sliding clutch-wheels N N' from the pinions M M'. This is accomplished by the inclined or beveled lugs H H' (formed or secured on 120 the inner sides of the rack-bars at or near their rear ends) coming in contact with the flanges d on the sliding clutches. These lugs or projections only come into play when the pressure-controller fails to operate, and they 125 serve to prevent the rams from being forced against the heads of the ram-cylinders.

It is evident that I may bevel the flange on the clutch-wheel and form the projections H

H' square, as shown in Fig. 8, without departing from the spirit of the invention in the least.

By this invention great power and speed 5 may be attained and a great saving in steam and fuel effected. By this arrangement of gearing and engines the power will be equally distributed and each engine compelled to do one-half of the work, no matter which ram may 10 be in operation.

Having thus fully described my invention, what I claim as new, and desire to secure by Letters Patent, is—

1. The combination of the two ram-cylinders, each being provided with two integral arms at their rear ends, the rams working in these cylinders, the rack-bars secured to the rear ends of these rams, the standards I I', rods L, connecting these standards with the 15 arms upon the rear ends of the cylinders, a shaft, K', journaled in the said standards I I', independent loose pinions upon this shaft adapted to engage the said rack-bars, independent sliding clutches upon the said shaft 20 K, adapted to engage the said loose pinions, and means for independently disengaging the said sliding clutches when the maximum pressure of the rams is obtained, substantially as described.

2. The combination of two ram-cylinders, rams for these cylinders, rack-bars secured to these rams, a shaft journaled in bearings to the rear of the rams, loose independent pinions upon this shaft, these pinions engaging the said rack-bars, sliding rotating 25 clutches adapted to engage these loose pinions, conduits C C', communicating with the forward ends of the ram-cylinders and leading to a common conduit, B, independent 30 check-valves in the said conduits C C', inde-

pendent cylinders Q Q', communicating with these conduits, pistons working in these cylinders, and suitable rods connecting the said pistons with the sliding clutches, substantially as and for the purpose specified.

3. The combination of the ram-cylinders and rams, the cylinders Q Q', communicating with the ends of the said ram-cylinders, pistons working in these cylinders Q Q', weighted and pivoted angle-levers S S', attached to the 45 said plungers, check-valves in the conduits leading from the forward ends of the ram-cylinders, rack-bars attached to the said rams, a shaft provided with loose pinions for operating these rack-bars, sliding clutch-wheels 50 adapted to engage the said loose pinions, and rods and levers connecting these sliding clutch-wheels with the said weighted levers S S', whereby the sliding clutch-wheels will be automatically disengaged when the maximum pressure of the rams is attained, substantially as herein set forth.

4. The combination of the rams and ram-cylinders, the rack-bars attached to the rams, a shaft, K, and gearing for driving these rack-bars, a spur-wheel, Z, secured on the said shaft K, a shaft, X, provided with a central pinion, Y, adapted to engage and operate the spur-wheels Z, spur-wheels A', secured on the ends of the shaft X, and driving-pinions engaging the said spur-wheels A', substantially as described.

In testimony whereof I affix my signature in presence of witnesses.

LEWIS MILLER.
